PACKAGING CONTAINER FOR LIQUIDS

Henry M. Chang, Bronx, N.Y., assignor to First Dynamics, Inc., New York, N.Y.

Filed Feb. 4, 1972, Ser. No. 223,799

Term of patent 14 years

Int. Cl. D9—03

U.S. Cl. D9—219

FIG.1

FIG.3

FIG. 1 is a top perspective view of a packaging container for liquids, showing my new design;

FIG. 2 is an elevational view as seen along the line 2—2 of FIG. 1; and

FIG. 3 is a bottom plan view.

I claim:

The ornamental design for a packaging container for liquids, as shown.
